MAGNETIC WORK-HOLDING DEVICE

Application filed March 30, 1931. Serial No. 526,448.

The present invention pertains to a magnetic work-holding device such as a magnetic jig, or top plate of a magnetic chuck, for use in connection with a magnetic field produced by any suitable means.

In the building of these devices, considerable difficulty has been encountered in properly fitting the pole separators into the magnetic material and in maintaining the original shape of the device after repeated use.

The object of this invention therefore, is to overcome these difficulties and is accomplished essentially by utilizing the shrinkage of cooling material for holding the magnetic and non-magnetic parts firmly together. One of the parts is in the nature of a core or skeleton consisting of suitably shaped pieces held together in spaced and substantially parallel relation. Spacer bars with apertures or projections are provided for supporting the pieces in this relation, and the joints between the bars and the pieces are sufficiently loose to permit the parts to have a slight movement or play relative to each other. The core thus formed is placed in a mold, and material of opposite magnetic character is poured therein to enclose the core except at the edges, which ultimately remain exposed at the surface of the finished product. The shrinkage of the poured material causes a slight displacement of the core parts because of the aforementioned loose joints therebetween. Consequently the core pieces are bound or clamped between the sections of poured material at the opposite surfaces thereof, and a structure is thereby obtained wherein the pole separators cannot possibly become detached from the pole pieces.

In constructing a non-magnetic core, a nickel-chromium alloy of 80% nickel and 20% chromium, such as nichrome IV may be used, and the magnetic material may be cast steel. The melting point of the core should obviously be high enough to resist the heat of

the molten material. The core, however, may consist of magnetic material with spacer bars and binders of non-magnetic material and the enclosing body of non-magnetic material. In such a case, the core may consist of iron 50 and the cast non-magnetic material may be chrome or bronze.

The invention is fully disclosed by way of example in the following description and in the accompanying drawing, in which 55

Figure 1 is a perspective view of a jig constructed according to the invention;

Fig. 2 is a perspective view of the core or skeleton used therein;

Fig. 3 is a perspective view of one of the 60 tie bars;

Fig. 4 is a perspective view of a modified construction;

Fig. 5 is a perspective view of one of the 65 elements thereof;

Fig. 5a is a detail section of a core, showing the loose joint employed in the cores shown in Figs. 2 and 4;

Fig. 6 is a transverse view of a modified 70 construction;

Figs. 7, 8 and 9 are sections on the lines 7—7, 8—8 and 9—9 respectively of Fig. 6, and

Fig. 10 is a perspective view of a modified 75 form of core.

Reference to these views will now be made by use of like characters which are employed to designate corresponding parts throughout.

Considering first the right angle jig shown in Figs. 1 and 2, it will be seen that this device is built around a core formed of a number of strips 1, the sides of which have the configuration and dimensions of the ends of the body to be formed. These members are arranged in parallel relation as shown in Fig. 85 2 and are thus held by rods 2 passed therethrough. In order to maintain a definite spacing between the members 1, there are provided spacing and connecting bars 3 having notches 4 in one of the edges thereof. 90

These notches interlock in similar notches 5 formed in the edges of the members 1 and of such depth that the outer edges of the members 4 are flush with the edges of the strips 1, as clearly illustrated in Fig. 2. The bars 3 are provided with suitable means, such as apertures 3', for attachment to the material subsequently to be poured into the core.

A magnetic work-holding device comprises 10 a magnetic body divided into separate poles by pieces of non-magnetic material inserted therein. According to the present invention, the skeleton may consist principally of either metal, and the other metal 6 is poured around 15 the core after placing the core in a mold of proper shape. It is preferred, however, that the skeleton consists of non-magnetic material and that the magnetic material be poured or cast around the same. In either case, the 20 connecting bars or rods should be non-magnetic in order to avoid a magnetic connection between adjacent poles.

The notches 4 and 5 are of slightly greater width than the thickness of the metal parts 1 25 and 3 to be respectively received therein, so that the joints between the members 1 and 3 are loose. This looseness provides sufficient play to permit these members to be drawn together a short distance commensurate with 30 the shrinkage of the cast metal in cooling. In other words, the parts of the core or skeleton are firmly embedded or clamped between blocks of cast metal at opposite sides. In this manner the magnetic and non-magnetic parts 35 are bonded together with a firmness comparable with that obtained by machining and fitting. Moreover, the labor necessary for such operations is avoided.

In the modification shown in Figs. 4 and 5, 40 the strips or separators 10 are of rectangular formation with notches 11 in the edges thereof. Each such member is formed with an aperture 12, and these apertures are concentric when the members 10 are parallel to each 45 other. Notched spacing bars 13 are inserted in the notches 11 to hold the members 10 loosely joined thereto in parallel relation as described in connection with Figs. 2 and 3. An open ended tube 14, consisting of the 50 same character of metal as the members 10 and 13, is passed loosely through the aligned apertures 12 and held therein.

The core or skeleton thus formed is placed in an appropriate mold having approximate- 55 ly the shape of the desired finished object, and material of opposite character mag- netically is poured therein. The cast metal forms a continuous rod in the tube 14, integral with and therefore connecting the end 60 blocks of solid metal. This rod therefore improves the firmness and rigidity with which the parts of the device are held together.

The loose joint previously mentioned is 65 shown in detail in Fig. 5a which will be as-

sumed to be a cross section taken through one of the spacing bars. The strip or pole separator, in the case of a non-magnetic core, is indicated by the numeral 15 and has a notch 16 in the edge thereof. The spacing bar 17 7 has a similar notch 18 which receives a portion of the member 15 directly beneath the base of the notch 16. The members 15 and 17 are thus interlocked at the notches thereof, and the notch of each member receives the 7 thickness of the other member loosely, as indicated by the numeral 19.

In the modification shown in Figures 6 to 9, each of the pole separating strips 20 has a V-notch 21 in the upper edge thereof, so that the 84 jig to be formed may be used as a V-block. The important feature of this construction, however, is that the block may be laid on either of two mutually adjacent sides, so that the V-notch may face upwardly or laterally. 84

The means for holding the pole separators 20 in spaced relation prior to pouring the magnetic material consists of tubes 22, 23 and 24 passed therethrough. The cast metal 25 poured around the core forms magnetic blocks at the sides of the pole separators 20. Obviously, the device is operative on a magnetic chuck when laid with its bottom face 26 in contact with the usual magnetic top plate, for in this position the poles are separated by 91 the members 20.

It will be seen by reference to Figs. 7, 8 and 9 that the tubes 22, 23 and 24 are of different lengths, extending from one of the faces 27 to successive poles. When this face is laid on the magnetic top plate, the metal within the tubes forms flux conductors to the successive blocks of metal at the sides of the pole separators. Inasmuch as these blocks are magnetically separated by the members 20 and 10 adapted to receive flux through the metal in the tubes, the device is operative as a magnetic jig when laid on the face 27.

Fig. 10 shows still another form of core for enabling the jig to be laid in any position in a given plane upon the top plate as in machining or grinding angular work. The pole separating strips 30 and 31 are provided at an angle to each other, the members of each series being spaced apart and parallel to each other. The members 30 and 31 may be positioned at an angle to each other because of notches 32 and 33 cut in the edges thereof so that these parts may be loosely interlocked in substantially the manner described in connection with Figs. 2 and 4. Each notch has a depth equal to the width of the unsevered part of the intersecting member, in order to contain the same completely, with the result that the members 30 and 31 intersect each other across the entire width thereof to form distinct and separate cells 34. This device is held together by a rod 36 passed through the members 30 and 31. The magnetic metal poured around the core is therefore divided 130

- in two directions into series of pole pieces, and the jig may be turned or adjusted on the top plate without destroying the polarity relations. 70
- 5 In all of the constructions herein described, the surfaces are obviously machined after the casting operation. The edges of the separating strips are exposed at the surfaces of the device and, being in direct contact with 10 metal of opposite magnetic character, form magnetic edges. When deemed necessary, the device may be heat treated to improve the magnetic properties and insure retention of shape. 75
- 15 The expression "magnetic character" as used herein and in the claims refers to the magnetizability or non-magnetizability of the metal rather than to the polarity of magnetized metal. 80
- 20 Although specific embodiments of the invention have been illustrated and described it will be understood that various alterations in the details of construction may be made without departing from the scope of the invention 25 as indicated by the appended claims. 85
- What I claim is:
1. A magnetic work-holding device comprising a plurality of spaced members, means loosely connecting said spaced members, a 90 cast material having a positive co-efficient of expansion and of opposite magnetic character enclosing said members and leaving certain edges thereof exposed at the surfaces of said material. 95
  - 35 2. A magnetic work-holding device comprising a plurality of spaced members, spacing bars having a loose fit with said members, a cast material having a positive co-efficient of expansion and of opposite magnetic character enclosing said members and leaving certain edges thereof exposed at the surfaces of said material. 100
  - 40 3. A magnetic work-holding device comprising a plurality of spaced members, an open-ended element passing through said members, and cast material having a positive co-efficient of expansion and of opposite magnetic character enclosing said members and filling said element while leaving certain 50 edges of said members exposed at the surfaces of said material. 110
  - 45 4. A magnetic work-holding device comprising two series of spaced members of equal width intersecting each other, the intersections being provided by means of loose notch joints bringing the intersecting edges of one series into the same planes as the intersecting edges of the other series, and material of opposite magnetic character at the sides of 55 the members, filling the spaces therebetween and leaving said intersecting edges exposed at the surfaces of said material. 120
  - 60 5. A work-holding device comprising a plurality of pole separators in spaced and substantially parallel relation, tubes of dif- 65 125
  - 65 130
